UNITED STATES PATENT OFFICE.

ALBERT C. WOOD, OF PHILADELPHIA, PENNSYLVANIA.

BOILER-FURNACE

1,097,598.

Specification of Letters Patent. Patented May 19, 1914.

Application filed July 8, 1913. Serial No. 777,348.

To all whom it may concern:

Be it known that I, ALBERT C. WOOD, a citizen of the United States, residing in the city of Philadelphia, county of Philadelphia, and State of Pennsylvania, have invented certain improvements in Boiler-Furnaces, of which the following is a specification.

My invention is a boiler furnace in which the heating gases flow downwardly from the place of primary combustion along elements of a steam generator extending below such place of primary combustion.

The leading objects of my invention are to secure high capacity and heating efficiency, economical use of space, automatic feeding of fuel, ready accessibility and convenience in operation.

In large boiler plants, the basement spaces under the fire room floors are generally utilized merely for the removal of ashes, and the location of the grates below steam generators frequently requires such dispositions to be made that parts of the generators and furnaces are too high above the fire floors to be conveniently accessible, necessitating very high boiler houses.

In my invention, in its preferred form, the furnace grate mechanism and place of primary combustion are located in proximity to the fire room floor, beneath the steam collecting shell, between upright sets of water circulating tubes and above the lower part of the water circulating system, over which the gaseous products of combustion flow below said grate mechanism. This arrangement permits the utilization of the otherwise waste space below the fire floors and further conserves space by the use of substantially upright water circulating and steam generating tubes. It also secures uniform, efficient and practically automatic feeding and combustion of the fuel. It further secures an efficient absorption of heat by the peculiar baffling and by the correlation of the furnace and generator so that the place of primary combustion is surrounded by elements of the generator and so that uniform distribution of the gases among the tubes is effected, and the tendency of the hot air streams of gases to flow in certain sections of the heating elements is obviated.

In the accompanying drawings, Figure 1 is a vertical sectional view taken transversely through a boiler furnace embodying

improvements of my invention; Fig. 2 is a transverse vertical sectional view of the same; Fig. 3 is a sectional elevation of a rocking grate comprised in my improvements; Fig. 4 is a broken sectional view taken transversely through the mechanism shown in Fig. 3; and Fig. 5 is a vertical sectional view of a modified construction.

The construction, as illustrated in Figs. 1 and 2, comprises the foundation 1, the walls 2 and 2' rising therefrom, and the floor 3 supported thereby, the walls inclosing a furnace chamber 4 communicating through a valved passage 5 with the flue 6 beneath the surface of the foundation.

Substantially upright, oppositely inclined banks of water tubes 7 are connected at their lower ends with shells or drums 8 and at their upper ends with headers 9, the drums 8 resting upon bearings 10 supported by the foundation 1, and the tubes 7 and headers 9 bearing against the walls 2. The drums 8 are connected together by the conduits 11, and the headers 9 are connected by nipples 12 with the steam collecting shells or drums 13, the latter being connected together by the conduit 14 and with the shells 8 by the conduits 15. Nipples 16 connect the shells 13 with shells or drums 17, and the latter are connected by substantially upright oppositely inclined tubes 18 with shells or drums 19 which communicate with the conduits 15. Tubes 20 connect the shells 13 with shells 21 exterior to the tubes 18, and tubes 22 connect the shells 13 with the shell 23 disposed between the sets of tubes 18.

In the lower part of the chamber 21, between the sets of tubes 18, is a circular grate 24 mounted on a journaled shaft 25 whereby it is adapted to be rocked, this grate being disposed midway between the shells 19 and coacting with the revoluble grate bars 27, disposed between it and the shells. A fuel inlet 28 extends downwardly between the respective shells 13 and 17 and is controlled by the revoluble valve 28' through which fuel is delivered to the chamber 24 upon the grate mechanism thereof.

Ash hoppers 29 are located below the chamber 24, provided with the doors 30 between the baffles 31 on the inner tubes 7 and shells 19, and have the valves 30' in the bottoms thereof. The hoppers discharge to the car 32 movable on the track 33 which is supported by the floor 34, the latter extending between the lower ends of the baffles 31.

The tubes 20 are inclosed by baffles 25 which form the passes 36 by which air is delivered from the inlet 37, between the upper ends of the tubes 18, to the fuel chamber 24; air is also admitted through the grate mechanism between the shells 19 to the chamber 24. The gaseous products of combustion are delivered to the combustion chambers 38, between the baffles 31 and 35 and beneath the baffles 39 and the shells 13, whence they flow in contact with the headers 9, downwardly along the tubes 7 between the walls 2' and 31, and around the shells 8 to the outlet 5 and duct 6, baffles 40 directing the gases along the lower ends of the tubes and valves 41 controlling the passes between the walls 2 and shells 8. The baffles 35 prevent the escape of green gases distilled from fuel in the top of the chamber 24 and compels such gases to pass out through a hotter, lower zone so as to effect more complete combustion.

The grate 25, as illustrated in Figs. 3 and 4, comprises wheels 25' fixed on the journaled shaft 26, rings 25" having a limited turning movement on the wheels, and the grate bars 25^a having the journals 25^b in the rings 25" and the slotted flanges 25^c engaged by the studs 25^d fixed to the wheels 25'. These grate bars are adapted to occupy the position shown at the right of Figs. 1 and 3 when rising and that shown on the left of these figures when descending, so that in their descending movement they are adapted for engaging and grinding down ashes in the bottom of the chamber 24, the operation turning the grate bars 27 and the ashes falling into the hopper 29.

As illustrated in Fig. 5, the foundation 11, the outer walls 2 and 2' which support the floor 3, and the intermediate walls 2^a with the wall 2^b thereabove, form the main chambers 4^a and the flue 6^a communicating therewith through the valved passages 5^a. The chambers 4^a have therein the banks of substantially upright, oppositely inclined tubes 7 with the shells or drums 8 connecting their lower ends and connected by the conduit 11, the tops of the tubes being connected with headers 9' which are connected by headers 9^a with a steam collecting shell or drum 13'. Headers 9^a, connected with the headers 9', are connected by tubes 12' with the drum 13', the tubes being inclosed by the baffling 29'. Headers 9^b and 9^c, connected with headers 9', are connected respectively with a header 9' by tubes 12^a and with the shell 13' by tubes 12^b. Tubes 18' and 18^a connect the headers 9^b and 9^c with the respective shells 19' and 19^a, which are connected by the respective conduits 19^a and 19^b with a conduit 15' communicating with the shell 13'. Tubes 16', covered by baffling 16'', are connected with the shell 13' and the shell 17'. Tubes 20', covered by baffling

35', connect the shell 13' with a shell 21', the latter being connected by a conduit 19^c with the conduit 15', and tubes 20'' connect the shell 21' with a shell 21''.

A revolving grate 25, journaled by the shaft 26, is disposed between the shells 19' and 21'', and a revolving grate bar 27 is disposed between the grate 25 and the shell 21''. Fuel is fed to the grate mechanism and the primary combustion chamber 24 from the inlet 27^a, through the chamber or passage 24' formed by the tubes 18'' and the grate 18^a on the tubes 18'. Air is admitted to the primary combustion chamber through the inlet 37', the chamber 36' and between the tubes 18''; also between the tubes 18' and through the perforated grate 18^a thereon, and through the grate mechanism comprising the parts 25 and 27.

The gaseous products of combustion flow from the chamber 24' between the tubes 20'' to the secondary combustion chamber 38', thence in contact with headers 9' and downwardly along the tubes 7 between the walls 2 and baffling 31, thence around the drums 8 beneath the floor 34, thence upwardly along the tubes 7 between the wall 2^a with the baffling extension 2^c thereon and the baffle 31' into contact with headers 9', and thence through the chamber 6^b, passage 9^a and flue 6^a, the green gases being directed downwardly through the hotter zones to complete their combustion by baffles 16'' and 35'.

It is to be understood that the terms upright or substantially upright, as used in the description and claims, means at an angle of more than forty-five degrees with a horizontal plane.

Having described my invention, I claim:

1. In a boiler furnace, the combination of a steam generator comprising a plurality of sets of substantially upright tubes, a grate combining with a set of tubes aforesaid for holding fuel in process of combustion, and means for carrying gaseous products of combustion evolved from said fuel in contact with a second set of tubes aforesaid beneath said grate.

2. In a boiler furnace, the combination of a steam generator comprising a plurality of sets of substantially upright water tubes, a grate combining with one or more sets of said tubes for holding fuel above the lower ends of one or more sets of said tubes, and means for carrying gaseous products of combustion downwardly in contact with parts of said last named tubes lower than said grate.

3. In a boiler furnace, a firing floor, a chamber extending below said floor, a generator having a plurality of sets of substantially upright tubes with their lower ends supported in said chamber below said floor and water tubes between sets of tubes first

- named, a grate between said sets of tubes first named and coacting with said second named tubes for holding fuel, and means for carrying gaseous products of combustion 5 along said sets of tubes first named through said chamber beneath said floor.
4. In a boiler furnace, a chamber, a grate in said chamber, water tubes for holding fuel on said grate, a set of substantially upright water tubes extending below said 10 grate, and means for carrying gaseous products of combustion downwardly along said last named tubes.
5. In a boiler furnace, a chamber, a grate in said chamber, a plurality of sets of substantially upright water tubes for holding fuel above said grate, banks of substantially upright water tubes in said chamber on opposite sides of said grate and sets of tubes 15 first named, steam collecting means connected with said tubes above said grate, and means for carrying gaseous products of combustion in contact with said tubes and steam collecting means.
- 20 6. In a boiler furnace, a chamber, a grate
- in said chamber, an ash hopper below said grate, water tubes above said grate for holding fuel thereon, banks of water tubes supported in said chamber below said grate, and steam collecting means connected with said 25 tubes above said grate, said grate and hopper being disposed between said banks of tubes and below said steam collecting means.
7. In a boiler furnace, a chamber, a plurality of banks of substantially upright 30 water tubes supported in said chamber, a grate between said banks of tubes, a plurality of sets of water tubes for carrying and holding fuel on said grate, steam collecting means connected with said tubes, and 35 means for introducing air between said second tubes to the fuel on said grate.
- In testimony whereof I have hereunto set my hand this 30th day of June, 1913, in the presence of the subscribing witnesses.

ALBERT C. WOOD.
